UNITED STATES PATENT OFFICE.

HENRY BULLARD, OF MIDDLETOWN, CONNECTICUT, ASSIGNOR TO THE
MIDDLETOWN PLATE COMPANY, OF SAME PLACE.

ICE-PITCHER.

SPECIFICATION forming part of Letters Patent No. 274,263, dated March 20, 1883.

Application filed January 24, 1883. (No model.)

To all whom it may concern:

Be it known that I, HENRY BULLARD, of Middletown, in the county of Middlesex and State of Connecticut, have invented new Improvements in Ice-Pitchers; and I do hereby declare the following, when taken in connection with the accompanying drawing and the letters of reference marked thereon, to be a full, clear, and exact description of the same, and which said drawing constitutes part of this specification, and represents a side view, partly in section.

This invention relates to an improvement in that class of ice-pitchers and vessels of like character which consist of a metal or other suitable material outer shell, inclosing an inner vessel of porcelain, glass, or like material, so as to leave a space between the outer wall and the inner vessel, and commonly called "double-wall pitchers," the object of the invention being to simplify and cheapen the construction; and the invention consists in the construction of the pitcher, as hereinafter described, and more particularly recited in the claims.

A represents the outer wall, which may be of any desirable shape, according to the requirements of the trade or taste of the manufacturer. At its upper end, upon the inside, an annular ledge, *a*, is formed.

B is the inner vessel, which is made from porcelain, glass, or other suitable like material, of so much less external diameter than the internal diameter of the outer wall as to leave a space, *b*, between the two.

At the upper edge of the inner vessel an outward annular projecting flange, *d*, is formed, which rests upon the ledge *a* on the outer wall, and so that the top of the inner vessel will stand flush with or a little below the upper edge of the outer wall, as shown.

Around the upper edge of the inner vessel is a groove, into which a suitable packing, *e*, is introduced. This packing may be of any of the known materials for so packing the joint as to prevent the escape of water. Around the top of the chamber is a cap or rim, *C*. This is in width sufficient to extend over both the outer and the inner wall. Upon its inner edge a flange, *f*, is turned downward inside the inner vessel, and at a little distance from

the top the flange turns inward and forms an annular ledge, *h*. This ledge *h* is for the purpose of supporting the ice-holder, which is made detachable from the pitcher, and so that ice may be placed in the ice-holder and then set into the pitcher, the flange on the ice-holder *D* engaging the ledge *h* on the flange *f*, so as to be supported within the pitcher.

The pitcher is provided with the usual spout, cover, and handle—that is to say, in such water-holders as are provided with handle and spout; but in such as are provided with a faucet only, then the handle and spout will be omitted, as in the usual construction, it being understood that my invention is applicable to the various classes of double-wall water-coolers.

The cap or rim *C* is soldered to the outer wall after the inner vessel is in place, the packing *e* being compressed by the rim, so as to prevent the escape of water over the outside of the inner vessel into the space between the two walls.

I claim—

1. The combination of the outer wall, *A*, constructed with the internal projection or rest, *a*, the inner vessel, *B*, constructed with an external projection, *d*, to rest upon the projection *a*, and with a groove around its upper edge, the rim *C*, soldered to the outer wall, extending over the inner vessel, with a flange therefrom extending down inside the inner vessel, and with a packing, *e*, between the rim and the top of the inner vessel, substantially as described.

2. The combination of the outer wall, *A*, constructed with the internal projection or rest, *a*, the inner vessel, *B*, constructed with an external projection, *d*, to rest upon the projection *a*, and with a groove around its upper edge, the rim *C*, soldered to the outer wall, extending over the inner vessel, with an internal projection or rest, *h*, for the ice-holder, and with a packing, *e*, between the rim and the top of the inner vessel, substantially as described.

HENRY BULLARD.
